POWER SUPPLY SYSTEM

Kurt Emde, Chicago, Ill., assignor to Zenith Radio Corporation, Chicago, Ill., a corporation of Illinois

Application February 12, 1940, Serial No. 318,422

5 Claims. (Cl. 171—97)

This invention relates to a power supply system for a device operable by electric currents differing in character and/or voltage, and more particularly concerns a novel circuit controlling arrangement through which such a device may be selectively connected with one or another of a plurality of sources of electric current supply.

The principal object of the invention is to provide an arrangement of the aforesaid character which is operable in a novel manner to not only effect connection of the device with a selected one or another of a plurality of sources of electric current supply, but to prevent connection of the device with more than one of such sources at a time, and to effect the connection of the proper power supply circuit of the device with the selected source of electric current supply. Another object of the invention is to have the novel manner of operating the arrangement so simple and so conveniently and obviously presented for use that understanding and caution upon the part of the user is not required, to the end that the power supply circuits of the device may not be connected with the wrong source of current and may not be connected with more than one of said sources at a time. Further explanation of these objects and other objects of the invention will appear in the description to follow.

While the invention is primarily designed for use in connection with the power supply circuits of radio receiving apparatus and will be so described, it will be evident that its usefulness is not confined to such apparatus, and I desire not to be limited thereto.

35 In the drawings—

Figure 1 is a perspective view, illustrating the back of a portable radio receiving set, with the demountable rear panel of the outer casing removed to disclose the arrangement of the principal elements of the construction hereinafter described as embodying my invention;

Figure 2 is a circuit diagram showing an arrangement, selected for illustrative purposes only, of the power supply circuits of radio receiving apparatus, with which are associated the circuit controlling switch and power service line plug employed in the herein described embodiment of my invention;

Figure 3 is a fragmentary vertical sectional view, upon an enlarged scale, taken upon the line 3—3 of Fig. 1, transversely through the circuit controlling switch, showing the power service line plug in switch-operating position;

Figure 4 is a vertical sectional view, taken upon the line 4—4 of Fig. 3, longitudinally through the

circuit controlling switch, but without the plug; and

Figure 5 is an inverted bottom plan view of the switch and plug of Fig. 3, taken upon the line and viewed in the direction of the arrows 5—5 of Fig. 4.

As is well known to those familiar with the radio art, certain types of radio receiving sets are designed for operation by electric current supplied either by power service lines or by battery. 10 The type of current supplied by the power service lines may be either A. C. or D. C., and the voltage may be much higher than that of the battery, and the battery current supply may be either from storage or secondary batteries or from dry-cell or primary batteries. Regardless of the type or voltage of the current available from the power service lines, and whether storage or dry-cell batteries be employed, it is important that, in such sets, the battery circuits be disconnected 20 when the power line circuits are connected, and it is customary to equip the sets with a manually operable battery switch for this purpose, but there is no provision against misadjustment of the switch. Where a single-throw battery 25 switch is provided and is inadvertently left closed when the power line circuit is connected, the result will be the draining of the battery, and if a double-throw change-over switch is provided for alternately connecting the battery circuit or the 30 power line circuit and it is left in the wrong position, the battery circuit is unintentionally employed and the battery exhausted, while the user, having plugged into the power service line outlet-socket, believes power service line current is 35 being supplied. It will be evident from the following description that the present invention provides against misadjustment of the switch.

For convenience in illustrating the embodiment of my invention in radio receiving apparatus, I 40 have shown in Figure 1 of the accompanying drawings the back of a portable radio receiver 1, the rear outer panel 2 of which has been demounted from the casing and set aside to disclose the inner panel 3, the storage brackets 4—4 45 secured thereto, the power service line cord 4 wound upon said storage brackets, the plug 6 attached to the free end of said cord, the battery leads 7, and the plug receptacle 8. The dry-cell or primary battery 9 is located at the bottom of 50 the receiver, forward of inner panel 3, as indicated by dotted lines. If the receiver is to be operated by electric current supplied by power service lines, the cord 5 may be unwound from the storage brackets 4—4 and the plug 6 plugged 55

into the usual wall-socket, as indicated in full lines at 10. When so connected, the plug is used as a circuit-connector and the receiver is supplied with electric current, either A. C. or D. C., as the case may be, from the power service lines through the cord 5. If desired, the rear outer panel 2 may be replaced in position to close the back of the casing, with the cord 5 extending through a notch (not shown) in the outer panel 10 2 similar to the notch 11 shown in the edge-part of inner panel 3. Simple means for holding the panel 2 in position to permit convenient removal and replacement thereof is provided, such as by stepping a pair of dowel-pins, one of which is 15 shown at 12, into the sockets 13-13 and pressing the catch-member 14 between the spring tongues of the retaining clip 15. Obviously, when the receiver is to be carried about, the plug 6 will be removed from the wall-socket 10, and the 20 cord 5 and plug 6 may be stowed within the space between the outer and inner panels, 2 and 3, respectively. If the receiver is to be operated by electric current supplied by the battery 9, the 25 prongs 16-16 of the plug 6 are pushed into the prong-receiving apertures 17-17 of the plug receptacle 8, as indicated in dotted lines in Figure 1 and as shown in Figures 3 and 5. When used in this way, the plug 6 serves as a key for 30 mechanically operating the change-over switch 20 in a manner to be described, but the prongs make no electrical contact and the cord 5 does not connect the receiver with any electric current supply.

Inner panel 3 is removably secured in position within the casing in any desired manner and is 35 apertured at 18 to provide access to the plug receptacle 8 and a passage for the battery leads 7, which are brought out therethrough to the rear of the panel and connected with the battery 9 through an aperture 19 by means of the four-pronged terminal plug 20. Battery 9 may be removed and replaced by disconnecting the terminal plug 20 therefrom and removing the inner panel 3.

Referring, now, to Figures 3, 4 and 5 of the 40 drawings, I have shown therein a change-over switch at 21, the particular interior construction of which will be described, but is not a part of this invention. It is to be understood that any switch construction may be employed which is 45 suitable for the purpose and method of operation hereinafter set forth. Plug receptacle 8 is preferably struck out and formed of stiff sheet metal and, when positioned with the switch thereabove as herein shown, comprises a horizontally extending table-portion 22 and two 50 downwardly turned vertical flange-portions 23 and 24. Flange-portion 23 is firmly secured preferably to the rear vertical wall of the metal chassis 25, as by screws 26-26, and flange-portion 55 24 is provided with the prong-receiving apertures 17-17. Switch 21 is firmly secured upon table-portion 22, as by screws 27-27. Table-portion 22 is bisected by a slot 28, one end-part of which extends a short distance down into the 60 flange-portion 24 and forms the upper one of the two prong-receiving apertures 17-17 therein. As shown in Figure 5, when the prongs 16-16 of plug 6 are pushed into the prong-receiving apertures 17-17, the upper one of said prongs 65 occupies the slot 28, one side of which is cut away to form a recess 29. A tongue 30 is bent from flange-portion 23 to extend horizontally therefrom toward flange-portion 24 just below the lower one of the prong-receiving apertures 70 75 17-17 and serves as a guide-support beneath

the lower one of the prongs 16-16, the upper one of said prongs being similarly guided by the lower surface of the switch-unit 21, the arrangement being such that, when the prongs 16-16 are pushed into the respective prong-receiving apertures 17-17, they will travel along and be guided between the tongue 30 and the bottom of the switch-unit 21.

Switch-unit 21 comprises a fixed contact-supporting plate 31 and a movable member 32, both being formed of insulating material, such as fibre or vulcanite, and encased within a two-part metal shield having a base-member 33 and a cap 34. Base-member 33 has a flat bottom-portion 35 and two upwardly turned side flanges 36-36. The opposite end-parts of bottom-portion 35 are provided with threaded openings for the attaching screws 27-27, and the upper edges of side flanges 36-36 are formed with tongue-clips 37-37. Movable member 32 slides upon the bottom-portion 35 between side flanges 36-36 and is formed with a downwardly projecting lug 38 which extends through an opening 39 in bottom-portion 35 and through the slot 28 and recess 29 in the table-portion 22 of plug-receptacle 8. An end wall plate 40 is secured to the side flanges 36-36 to close one end of the trough formed thereby, and a coiled compression spring 41 is positioned between the plate 40 and the adjacent end of the movable member 32, the action of the spring being such that, when the prongs 16-16 of plug 6 are removed from the respective prong-receiving apertures 17-17, it will hold the movable member 32 in the position illustrated in Figure 4, wherein the lug 38 engages the right-hand end of the opening 39 and is partly across slot 28 and partly within recess 29. As viewed in Figures 3 and 5, the right-hand and rear vertical surfaces of the lug 38 are beveled or backed away, as at 42, so that, when the upper one of the prongs 16-16 is pushed into the slot 28, the rounded end thereof will engage with the beveled surface 42 of the lug and force it to one side out of the slot 28 and fully into the recess 29, compressing the spring 41 and holding the movable member 32 in its leftward position as long as the slot 28 is occupied by the upper prong. Obviously, upon removal of the prong from the slot, spring 41 will return the movable member to its rightward position.

Plate 31 is supported upon the upper edges of side flanges 36-36 and is held in fixed position thereupon by the tongue-clips 37-37, which register with corresponding notches in the edge of the plate and are bent inwardly over the top thereof, as shown at 43. Two sets of three contacts each, 44 to 46 and 47 to 49, respectively, are arranged in line in plate 31, the contacts being formed and secured in position in the manner illustrated in Figure 3, each contact having an upwardly extending arm 50 to which one of the circuit leads, to be later described in connection with Figure 2, is soldered or otherwise connected. The contact arms 50 and the ends of the leads connected thereto are enclosed by the metal shield cap 34, which is lined with insulating material 51 and provided at the top with an opening 52 for the passage of the leads therethrough. Cap 34 removably fits down over and surrounds the upstanding parts of base-member 33.

Directly below the line of contacts 44 to 49, the upper face of movable member 32 is channeled longitudinally, leaving the upstanding side flanges 53-53 for guiding engagement with the

under face of plate 31, and a pair of cylindrical pockets 54—54 are formed in the body of the member, opening upwardly into the bottom of the channel. Each of said pockets 54—54 houses a 5 coiled compression spring 55 which surrounds the central stem and acts upwardly beneath the flat circular head of one of two bridging contacts 56—57. The diameter of the flat circular head of each of the two contacts 56—57 is sufficient to 10 bridge two of the contacts 44 to 49, against which it is held by the action of its spring 55. As shown in Figure 4, when the movable member 32 is in its rightward position, contact 56 will bridge contacts 45 and 46 and contact 57 will bridge contacts 48 and 49, while, as indicated by dotted lines in Figure 2, when the member 32 is in its 15 leftward position, contact 56 will bridge contacts 44 and 45 and contact 57 will bridge contacts 47 and 48.

20 It is to be understood that the successful employment of my invention is not in any sense dependent upon the particular arrangement shown in Figure 2. The circuits therein diagrammed are intended to illustrate a practicable manner 25 of connecting the several battery leads 7 and the power service line leads 58—59 of the cord 5 with the change-over switch 21, and the employment of the switch to effect the proper adjustment of the power supply circuits of the device in accordance with the character and/or voltage of 30 the electric current supplied through connection of the device with the battery or with power service lines. I have already mentioned that a single-throw battery switch may be employed, if 35 desired, and the circuit connections therewith would differ somewhat from those of Figure 2, but I prefer the double-throw change-over switch herein shown and described to insure the disconnection of the power service line supply when 40 the battery is connected, thereby avoiding the possibility of employing a separate plug to operate the switch and effect the connection of the battery while the power service line is connected and thereby frustrate one of the principal objects 45 of my invention, namely, to prevent connection of the device with more than one source of electric current supply at the same time.

Since this invention is not necessarily concerned with the circuits of the radio receiving 50 set, they have not been illustrated, but it may be explained that the B-plus lead 60 extends to the plate circuit of the first audio frequency tube, B-plus lead 61 extends to the plate circuits of the other tubes, and A-plus lead 62 is connected 55 with the filament or cathode-heating circuit, and, as is customary, these circuits are finally completed through a common ground return.

Still referring to Figure 2, wherein movable member 32 of switch 21 is indicated in full lines 60 in its rightward position, it may be seen that, upon inserting plug 6 in a power service line socket, as indicated at 10 in Figure 1, and closing the "on-off" switch 64, power service line current will be supplied to the device as follows: 65 lead 58 to rectifier 65, thence through lead 66 to A-plus lead 62 and ground, and through lead 67, contacts 49, 57 and 48, and lead 68 to B-plus lead 61 and ground, also through branch-lead 69 and switch 64 to B-plus lead 60 and ground, the several circuits being completed through ground 63, switch 64, lead 70, contacts 45, 56 and 46, and lead 71 to lead 59. When movable member 32 is in its leftward position, as indicated by dotted lines, the power service line will be disconnected, 70 since contacts 46 and 49 will not be engaged by

the respective bridging contacts 56 and 57, and battery current will be supplied to the device as follows: A-plus lead 72 directly to A-plus lead 62 and ground and back through ground 63, switch 64, lead 70, contacts 45, 56 and 44, to A-minus lead 73; also B-plus lead 74, through contacts 47, 57 and 48, and lead 68, to B-plus lead 61 and ground, and through branch-lead 69 and switch 64 to B-plus lead 60 and ground, returning through ground 63 and B-minus lead 75. 10

I claim:

1. A power supply system for radio receiving apparatus operable by electric current of one character when connected with one source of current supply and operable by electric current of a different character when connected with a different source of current supply, said system comprising a circuit connecting plug having a contact prong for connecting said apparatus electrically with said one source of current supply, a 20 mechanically operable switch controlling the connection of said apparatus with said different source of current supply, and a plug receptacle having a prong-receiving aperture to receive the contact prong of said plug, said aperture being so arranged with respect to said switch as to permit the insertion of the contact prong of said plug into said aperture to mechanically operate said switch and thereby effect the connection of 25 said apparatus with said different source of current supply. 30

2. A power supply system for radio receiving apparatus operable by electric current of one character when connected with one source of current supply and operable by electric current of a different character when connected with a different source of current supply, said system comprising a circuit connecting plug having a pair of contact prongs for connecting said apparatus electrically with said one source of current supply, a circuit switch having a movable member controlling the connection of said apparatus with said different source of current supply, and a plug receptacle having a pair of prong receiving apertures to receive the contact prongs of said plug, one of said apertures being so arranged with respect to said switch as to permit the insertion therein of the respective one of the prongs of said plug to engage with and operate the movable member of said switch and thereby effect 50 the connection of said apparatus with said different source of current supply. 45

3. A power supply system for radio receiving apparatus operable by electric current of one character when connected with a first source of current supply and operable by electric current of a different character when connected with a second source of current supply, said system comprising first and second circuit connections for connecting the apparatus with said first and second sources of current supply, respectively, a circuit connecting plug in said first circuit connection having a contact prong for connecting said apparatus electrically with said first source of current supply, a mechanically operable change-over switch acting upon adjustment thereof to open either one and close the other of said circuit connections, and a plug receptacle having a prong receiving aperture to receive the contact prong of said plug, said aperture being so located with respect to said switch as to permit the insertion and withdrawal of the prong of said plug into and from said aperture to control the adjustment of said switch and thereby determine 70 75

which of said circuit connections shall be opened or closed.

4. A power supply system for radio receiving apparatus operable by electric current of one character when connected with a first source of current supply and operable by electric current of a different character when connected with a second source of current supply, said system comprising first and second circuit connections for connecting the apparatus with said first and second sources of current supply, respectively, a circuit connecting plug in said first circuit connection having a contact prong for connecting said apparatus electrically with said first source of current supply, a mechanically operable change-over switch acting upon adjustment thereof to open either one and close the other of said circuit connections, and a plug receptacle having a prong receiving aperture to receive the contact prong of said plug, said aperture being so located with respect to said switch as to permit the insertion of the prong of said plug into said aperture to effect the adjustment of said switch to open said first and close the second of said circuit connections.
5. A power supply system for radio receiving apparatus operable by electric current of one

character when connected with a first source of current supply and operable by electric current of a different character when connected with a second source of current supply, said system comprising first and second circuit connections for connecting the apparatus with said first and second sources of current supply, respectively, a circuit connecting plug in said first circuit connection having a contact prong for connecting said apparatus electrically with said first source of current supply, a circuit change-over switch having a movable member operable in one direction to close the first and open the second of said circuit connections and operable in the other direction to open the first and close the second of said circuit connections, means acting upon said movable member to operate it in said one direction, and a plug receptacle having a prong receiving aperture to receive the contact prong of said plug, said aperture being so located with respect to said switch as to permit the insertion of the prong of said plug into said aperture to act upon said movable member to operate it in said other direction against the influence of said means.

25

KURT EMDE.
